CHESTER A. MUIR AND CECIL A. TAYLOR, OF SAYRE, PENNSYLVANIA.

PROJECTILE.

1,311,285.

Specification of Letters Patent. Patented July 29, 1919.

Application filed December 28, 1917. Serial No. 209,335.

To all whom it may concern:

Be it known that we, CHESTER A. MUIR and CECIL A. TAYLOR, both citizens of the United States, residing at Sayre, in the county of Bradford and State of Pennsylvania, have invented certain new and useful Improvements in Projectiles, of which the following is a specification.

This invention relates to projectiles, and 10 more particularly to a shrapnel shell.

One of the main objects of the invention is to provide a shrapnel shell of simple construction and operation so constructed as to cover a comparatively great area when exploded. A further object is to provide a shrapnel comprising a main shell in which are mounted a plurality of supplemental explosive members carrying shrapnel which will be distributed by the explosion of the 20 main shell, and will subsequently explode so as to scatter the shrapnel carried thereby over a great area. Further objects will appear from the detailed description.

In the drawings:

25 Figure 1 is a central longitudinal view through a shell constructed in accordance with our invention, one of the supplemental explosive members being shown in section.

Fig. 2 is a section taken substantially on 30 line 2—2 of Fig. 1.

The body 1 of the shell is of cylindrical shape being cast in the usual manner from steel tempered so as to be shattered into a great number of small particles by the force 35 of the explosion, this body being provided with a base 2. The forward end of body 1 is open and is interiorly threaded to receive the threaded neck 3 of the head 4 in the forward end of which is secured the timer 40 5, the head and timer being of standard construction. A tube 6 is mounted in body 1 adjacent the wall thereof and extends the full length of the body, the forward end of this tube being closely adjacent the inner 45 end of neck 3 of the head. Tube 6 is provided with a longitudinally extending series of spaced inwardly directed apertures 7. Mounted within the body 1, are a plurality of hollow spheres or balls 7. A nipple 8^a

50 is threaded into each ball so as to communicate with the interior thereof. In practice, we mount four or more of these balls in the body of the casing, the spaces between the balls being filled with a charge of some 55 suitable explosive such as dunnite, indicated by 9. At each end of the casing we provide

a charge 10 of gun powder, and the tube 6 is also filled with a charge 11 of gun powder. The time fuse carried in the head 4 acts to ignite the powder charge in tube 6, this 60 charge acting to instantaneously ignite the charges 10 and 9 through the openings 7 in the tube. This results in the explosion of the shell the body of the shell being shattered into small fragments and the balls 65 being scattered in different directions from the shell. Each ball 8 is approximately $\frac{3}{4}$ filled with shrapnel 12 which are secured therein by rosin poured into the ball so as to flow about and between the shrapnel in 70 the usual manner. An explosive charge 13 of dunnite or other suitable explosive is then poured into the ball above the shrapnel 12, after which the nipple 8^a is secured in position, the nipple being also filled with the 75 explosive. It will be evident that, when the shell is exploded, the explosive charges of the balls 8 will be ignited so that, when the balls are scattered from the shells, they will also explode so as to discharge the 80 shrapnel carried thereby over a comparatively great area doing a great deal of damage. By this means, we insure that the shrapnel will be distributed throughout a 85 relatively large area instead of being discharged within a relatively small area, as in the present type of shrapnel, thus greatly increasing the efficiency of a shrapnel shell of a given caliber.

What we claim is:

1. In a projectile, a hollow body, a supplemental explosive member disposed therein, a fused tube disposed removably longitudinally and eccentrically of the body in engagement with the inner surface of the 95 wall of the body and said tube being held against displacement by said member, means to ignite the fuse of the tube and means to explode said supplemental member through the action of the fuse. 100

2. In a projectile, a hollow body, supplemental explosive means disposed therein, a bursting charge in contact with said means and with the body, priming charges, one priming charge being at each end of the 105 bursting charge, and priming charge means for igniting said priming charges and bursting charge.

3. In a projectile, a hollow body, supplemental explosive means therein, a removable 110 fuse tube, a detachable closure member for the body preventing longitudinal displace-

ment of the tube from the body, said means and body preventing lateral displacement of the tube, means to ignite the fuse of the tube, said body having priming charges, and 5 a bursting charge intermediate the priming charges in contact with the supplemental explosive means and the body for ignition from said fuse, and said supplemental explosive means having fuse mechanism for 10 ignition from said charges.

4. In a projectile, a casing having explosive means therein, fuse means therefor including a tube open at both ends and said tube extending into the casing and beyond 15 the inner surface of the wall thereof to form an abutment for its charge to prevent undue escape thereof.

5. In a projectile, a hollow body, supplemental explosive means therein, a fused tube 20 disposed removably, longitudinally and eccentrically of the body for engagement with the inner wall of the body and said means, and being held against displacement laterally by said wall and said means, a detachable closure member for the body prevent- 25

ing longitudinal displacement of the tube, priming charges adjacent opposite ends of the supplemental explosive means, a bursting charge in contact with the supplemental explosive means and the body, said tube 30 being provided with means of communication with said charges, said supplemental explosive means including a fused member open at both ends and extending thereinto beyond the inner surface of its wall to form 35 an abutment for the charge to prevent undue escape thereof, and said removable closure member having fused means for operation to ignite the fuse of the said first mentioned tube, to ignite the charges from 40 said fuse and ignite the fuse of the supplemental explosive members therefrom.

In testimony whereof we affix our signatures in presence of two witnesses.

CHESTER A. MUIR.
CECIL A. TAYLOR.
